POSTAGE METER

Luther L. Mack, South Pasadena, Calif., assignor
to U. S. Postal Meter Corporation, a corporation
of Delaware

Application July 16, 1930, Serial No. 468,418

18 Claims. (Cl. 101—91)

This invention relates to postage meters, and the main object is to provide a mechanism adapted to be set by the postal authorities to print a predetermined amount of postage and thereafter locked against unauthorized access, and particularly arranged with a plurality of printing dies of different denominations for selective operation.

Another object is to provide a rotatable printing member having a plurality of extensible printing dies of different denominations mounted thereon, together with means for rendering said printing dies selectively operable.

A further object is to provide a dual register including an ascending unit and a descending unit for maintaining a total and balance record of the impressions made by the machine, together with means connected with the printing means whereby said registers will be simultaneously operable for deducting the amount of the postage printed in each operation from the descending register and for adding the same to the ascending register.

Another object is to provide an automatic mechanism for feeding the mail matter directly to and discharging the same from the printing means.

Other objects may appear as the description progresses.

I have shown a preferred form of my invention in the accompanying drawings, in which Fig. 1 is a front elevation of the assembled mechanism.

Fig. 2 is a transverse sectional elevation of the same on line 2—2 of Fig. 1.

Fig. 3 is a sectional elevation of the printing member on line 3—3 of Fig. 2.

Fig. 4 is a fragmentary sectional elevation on line 4—4 of Fig. 2.

Fig. 5 is a fragmentary sectional elevation on line 5—5 of Fig. 2.

Fig. 6 is a sectional plan of line 6—6 of Fig. 5.

Fig. 7 is a fragmentary sectional elevation on line 7—7 of Fig. 5.

Fig. 8 is a sectional elevation on line 8—8 of Fig. 5.

Fig. 9 is a perspective view of a trip device such as is shown in Fig. 5, cooperating with other devices for rendering the printing member operative when a letter is advanced to the printing means prior to a printing operation.

Fig. 10 is a sectional plan of the machine on line 10—10 of Fig. 2.

Fig. 11 is a sectional elevation on line 11—11 of Fig. 2.

Fig. 12 is a sectional elevation on line 12—12 of Fig. 2.

Fig. 13 is a sectional elevation on line 13—13 of Fig. 2.

Fig. 14 is a sectional elevation on line 14—14 of Fig. 2.

Fig. 15 is a sectional elevation of the printing member on line 15—15 of Fig. 3.

Fig. 16 is a section of the meter housing on line 16—16 of Fig. 2.

Fig. 17 is a perspective view of an intermittent gear unit for operatively connecting the printing member with the registers of the meter.

Fig. 18 is a view of an impression made by the printing member on a piece of mail matter.

In the consideration of this invention, attention is called to Letters Patent Nos. 1,527,365 and 1,527,366, issued Feb. 24, 1925, and Patent No. 1,796,296, dated Mar. 17 1930 all of which relate to postage meters but are adapted to print only a single denomination of stamp.

As shown particularly in Fig. 2 my present invention embodies a housing 1 with a base 2. Said housing is covered at its rear end by means of a detachable cover 3 and is provided with a forwardly extended meter housing 4 which is closed by means of a permanently affixed cover 5. The meter housing extends forwardly of a vertical partition 6 and connects with a rearwardly extended sub-housing 7 enclosing a compartment 8 against access, the compartment 8 being in communication with the meter compartment 9. The meter cover 5 is held in position on the meter housing 4 by means of a pair of screws 10, 10 which extend into the housing 4, and the heads of said screws are covered by means of plugs 11, 11 which are incapable of removal, thereby preventing access to the screws.

One side of the meter housing 4 is provided with a door 12 which is hinged on a lug 13 extending outwardly from the partition 6. Centrally of the meter housing and at the top thereof I provide a lock 14 suitably secured in a recess 15 of the cover 5 of the housing and provided with a key operated cylinder 16 which is connected with a barrel 17 rotatably held in a bore 18. Said barrel has a recess 19 formed therein which receives a tongue 20 on the door 12 for holding the door in locked position, as shown in Fig. 12.

The meter compartment 9 encloses a pair of commonly operated register units 21 and 22, each of which embodies a plurality of discs 23, 23, etc., rotatable on shaft 24 and 25 respectively. The unit 21 is of ascending series, while the unit 22 is of descending series.

opposite the door 12 is of descending series, and the arrangement of said registers is in all respects substantially similar to the devices shown in my hereinabove described pending application for patent. The unit discs of the two registers are provided with driven gears 26 and 27 which mesh with a common gear 28 on a shaft 29. The shafts 24, 25 and 29 are journaled in opposite portions 30 and 31 of a register supporting bracket 32 mounted in the meter compartment 9. Said bracket also supports other shafts 33 and 34 which carry sets of intermittent gear pinions 35, 36, etc., associated with the two registers so as to operate said registers speedometer fashion to a common extent at each operation of the machine.

One side of the meter housing 4 and also the door 12 above the registers 21 and 22 respectively, are provided with apertures 36 and 37 which are closed by means of transparent elements 38 for rendering the registers visible at the top of the meter.

Each of the discs 23 of the descending counter unit 22 is provided with a notch 39 adapted to be engaged by the free end 40 of the locking bar 41 which is fixed to a shaft 42 journaled in the opposite sides of the bracket 32. The notches 39 are so positioned on the discs 23 that when "0" on each of the discs is visible thru the aperture 37 the notches will be alined with each other 30 and engaged by the portion 40 of the member 41 for preventing the further rotation of the counters until reset by authorized officials of the Post Office Department.

The descending register unit 22 may be suitably arranged so that the discs 23 may be set by authorized parties when the member 41 is disengaged therefrom so as to correspond to a predetermined number of impressions for which payment has been made to the Post Office. This feature is fully described in my said pending application for patent.

Mounted below the meter housing 9 on a transverse shaft 43 I provide a rotatable printing cylinder 44 which, as shown in Fig. 11, has a quartet of upwardly extending arcuate ribs 45, 45, etc., which are spaced apart at their extremities to provide peripheral recesses 46, 46, etc. Forwardly of the register bracket and on the portion 30 thereof I provide a pair of levers 47 and 48 in the plane of the ribs 45 on the printing cylinder. The lever 47 is suitably fixed to shaft 42 while lever 48 is pivotally on a screw 49 attached to the bracket 32. Levers 47 and 48 interlock as shown in Fig. 11, one of said levers being provided with a head 50 and the other with a recess 51 for receiving said head. Also one of said levers, preferably the lever 48, is provided with a depending lug 52 which, when the register is unlocked and in readiness for operation will be held normally upwardly from the ribs 45, as shown in Fig. 11. This is effected by the interlocking of levers 47 and 48 and the rigid connection of lever 47 with member 41 thru the shaft 42. Lever 48 is urged downwardly by means of a spring 53 which is wound around the body of screw 49 and has its opposite ends attached respectively to the head of said screw and to the body of the lever. Thus when the machine is operated the head 40 of member 41 will ride on the peripheries of the register discs 23 and the lug 52 will be prevented from seating in one or the other of the recesses 46 on the printing cylinder.

Shaft 43 is journaled at its rear end in a bearing 54 which is formed on a skeleton frame member 55 attached at its base 56 to the base 2 of

the frame and by means of a foot 57 to the rear wall 58 of the housing extension 7. The printing cylinder 44 includes a pair of laterally spaced members 59 and 60 which are suitably held together by means of screws 61, 61, etc., extending thru the member 60 and into tangentially disposed lugs 62, 62, etc., which are arranged at regular intervals around and are formed on the member 59. The printing cylinder 44 is provided with a plurality of radially extensible printing dies 63, 63, etc., which are slidably disposed between the members 59 and 60 and have ribs 64 and 65 on the outer sides thereof adapted to engage keyways 66 and 67 formed on the inner sides of members 59 and 60 respectively. Thus the printing dies 63 are guided in their radial movement on the members 59 and 60.

The printing dies have printing faces 68, 68, etc., which are engraved or formed as shown in Fig. 18 to print authorized indicia in lieu of stamps affixed, as at 69. The printing dies 63 are arranged for selective operation and vary only as to the denomination of the stamp indicia thereon. I have shown four of such dies in the drawings, which, for instance, may be arranged to show 1¢, 2¢, 4¢ and 5¢ denominations, or other denominations as may be desired. In order to render the printing dies selectively operable at will I provide means for selectively fixing the printing cylinder to its shaft 43 at different points so that the printing dies may be properly positioned for imprinting indicia upon letters or cards which are fed to the printing means. I may accomplish this result by any one of a number of means, but I have shown a simple means in the drawings, particularly in Fig. 2.

The means shown includes a cap 70 which is fixed to the forward end of shaft 43 by means of a pin 71 or otherwise. Said cap has a single lug 72 projecting from the periphery thereof and adapted to selectively engage any one of a series of radially disposed notches 73 formed in a collar 74 which encompasses the shaft 43. The number of the notches 73 corresponds to the number of the printing dies 63. The collar 74 has a recess 75 therein in which a coil spring 76 is mounted around the shaft 43 and is compressed between the inner end of cap 70 and the bottom 77 of the recess 75.

The collar 74 has a bored extension 78 which is journaled in a bearing 79 on the front wall 5 of the meter housing and said extension is adapted to receive a hollow extension 79' of the printing cylinder member 60. The collar 74 is keyed to the extension 79' so that the collar will rotate with the printing cylinder 74. The extension 79' carries a gear 80 which is fixed thereto and which meshes with a similar gear 81 above the shaft 43. Gear 81 is fixed to a short shaft 82 which is journaled in a bearing 83 on the meter housing and in a plate 84 attached to the meter cover 4 as shown in Figs. 2 and 11.

A hand crank 85 may be attached to an extended end of shaft 82 for manually operating the machine, thereby rotating the printing cylinder 44 and associated parts, as hereinafter described. The member 44 of the printing cylinder is provided with a cam 44' which has a boss 86 extending rearwardly thru the member 59. Said boss has a reduced portion 87 and a further reduced 70 and threaded portion 88 which is screwed into a cap 89, and said cap is rotatably mounted in a bearing 90 held on the rear wall 58 of the meter compartment 8.

The portion 87 of boss 86 carries a composite 75

intermittent gear member 91 which is confined between the end of boss 86 and the cap 89. The gear 91 is tightly fixed to the boss 86 so that the gear will revolve with the printing member 44 at all times. The gear 91 is provided with several series of gear teeth, as at 92, 93, 94 and 95, which are correspondingly spaced apart and are adapted to be associated with the printing dies 63 respectively. The number of teeth in each series 10 on the gear will correspond to the denomination of stamp on the associated printing die. For instance, as shown, two teeth on the gear will correspond to a 2¢ denomination of stamp, four teeth to a 4¢ stamp, etc.

15 The cam 44' is longitudinally slidable on the shaft 43 together with the gear 91 and the cap 89, and said cam is permanently fixed to and for rotation with the shaft 43 by means of an elongated key-way 96 and a key 97 on the boss 86 20 and shaft 43 respectively. The cam 44' is normally held at its extreme right hand position, as shown in Fig. 2, by means of a spring 98 which compresses between the member 60 of the printing cylinder and the central portion of cam 44'. 25 The outer face of the cam has three pairs of longitudinally projecting arcuately formed and spaced ribs 99, 99 etc. The inner and outer faces of said extensions are concentric with the axis of the printing cylinder. The cam also has a single 30 inwardly inclined extension 100. The pairs of extensions 99 and the single extension 100 are spaced apart uniformly, as shown in Fig. 3, and are aligned respectively with the several successive printing dies 63.

35 The printing dies 63, 63 etc. when inwardly extended to normal positions, as shown in Figs. 2 and 3, are provided with pairs of arcuate grooves 101, 101 corresponding in positions to the extensions 99, 99 on the cam and also with relatively 40 central inwardly inclined grooves 102 corresponding in position and form to the single extension 100 on the cam. It will be noted that the inner extremities 103 of the inclined grooves 102 parallel the axis of shaft 43 so as to permit the inner 45 faces of the extensions 99 to move thereover. Likewise the outer extremities of the straight grooves 101 are beveled to correspond to the outer face of the extension 100. This particular form of grooves and extensions permits the rotation of 50 printing members 63 relative to the cam 44' for the purpose of selectively rendering only one of the several printing members operative and prevents the extension of any of the dies during such operation.

55 The particular printing die 63 which is operatively associated with the single inclined extension 100 is the one which is operative while all of the other dies are inoperative, and moreover prevented from extension into operative positions 60 when the operative die is extended for printing operation. Thus, as shown in Fig. 2, when the cam 44' is moved forwardly on shaft 43 against the tension of spring 98 the straight extensions 99 on the cam will move into the correspondingly 65 formed grooves 101 of the three inoperative dies, while the inclined extension 100 will move into the inclined groove 102 of the operative die and force said die outwardly into printing position.

On the rear end of shaft 43 I mount a gear 104 70 which has on its forward side an internal cam 105. Intermediate the gear and the rear wall 58 of the housing I provide a yoke 106 which is pivotally mounted at 107 on a bracket 108, said bracket being either attached to or formed on 75 the housing 7. Said yoke has a lateral extension

109 which carries a follower roller 110 in engagement with the inner periphery of cam 105. The yoke also is provided with a bifurcated extension 111 which straddles the shaft 43 and engages a washer 112 intermediate the yoke and the cap 89. The cam 105 has a segment 113 which is eccentric with respect to the remainder of the cam so that during each revolution of shaft 43 and cam 105 the yoke 106 will be swung on its axis so as to force the cam 44' forwardly into 10 operative engagement with the printing dies 63.

As hereinbefore stated the shaft 43 may be rotated manually by means of the hand crank 85 or optionally by means of a drive pulley 114 and a belt 115 arranged to be connected with a suitable 15 source of power. The pulley 114 is mounted on a counter-shaft 116 journaled in the frame 55 and also in the rear wall 58 of the housing and carries a pinion 117 which meshes with the gear 104.

Cooperating with the printing cylinder 44 I provide an impression roller 118 having a frictional band thereon which at all times engages the peripheries of the members 59 and 60 and is adapted to hold the pieces of mail matter in contact with the printing dies 63. Said roller is mounted on a 20 spindle 119 journaled in the ends 120, 120 of the yoke 121 which is pivotally held on a sleeve 122 carried in a bearing 123 on the web 6 of the housing. Said yoke has a depending arm 127 which is connected at 128 with a rod 129 which is 25 slideable in a boss 130 on the base 2 of the machine and is resiliently held in contact with the members 59 and 60 of the printing cylinder by means of a compression spring 131 carried on the rod 129, as shown in Fig. 11. The impression roller 30 shaft 119 is connected by means of a universal joint 132 with a short shaft 133 which is journaled in the frame 55 and carries a gear 134 which meshes with the main gear 104 by means of which motion is communicated to the impression roller. 35

Pieces of mail matter are adapted to be fed successively to the printing cylinder by means of the mechanism shown in Figs. 1 and 10. Said means includes a pair of parallel shafts 135 and 136 longitudinally spaced apart on the machine, 40 as seen in Fig. 1. The shaft 136 is journaled in the frame 55 in a bearing 137 on the main housing and in an out-board bearing 138 on a bracket 139 attached to the base 2. Said shaft carries a pair of laterally spaced pulleys 140 and 141 which 45 are aligned with similar pulleys 142 and 143 respectively on the shaft 135. The aligned pulleys 140 and 142 and 141 and 143 are connected by means of resilient belts 144 and 145, whereby motion is 50 communicated to the shaft 135.

The shaft 136 is driven by means of a gear 136' adjacent the frame 55 which meshes with an idler gear 153' loosely mounted on a rock shaft 153, and the idler gear in turn meshes with the gear 134 on shaft 133. Shaft 135 is driven from the shaft 136 55 by means of the belts 144 and 145. Intermediate the pulleys 140 and 141 on the main feed shaft 136 I provide a friction driven feeding wheel 147 which includes a hub 148 loosely held on shaft 136 and a pair of laterally spaced flanges 149 fixed 60 to the hub. The pulleys 140 and 141 being fixed to the shaft 136, motion is communicated to the feeding wheel 147 by means of a friction plate clutch 150, one of which devices may be installed intermediate each of the pulleys 140 and 141 and 65 the adjacent ends of the hub 148.

The hub 148 may be bored at 151 to receive a compression spring 152 which encompasses the shaft 136 and holds the plates 150 in frictional contact.

Intermediate the feed pulleys 140 and 141 and the impression roller 118 I provide a transverse rock shaft 153 which is journaled at its opposite ends in the frame 55 and the bracket 139, and intermediate said members is additionally journaled in the sleeve 122 on the main housing. Said rock shaft carries a follower arm 154 fixed thereto which has a roller 155 on its free end adapted to engage the outer periphery of cam 105. Said cam 105 is provided on its outer periphery with a raised segment 156 by means of which the shaft 153 is rocked in a clockwise direction, as seen in Fig. 11. Forwardly of the sleeve 122 the rock shaft is provided with an arm 157 which normally engages a shoulder 158 on the hub of the feed wheel 147 and prevents the rotation of the feed wheel during a major portion of a revolution of the cam 105. The arm 157, however, is released from the feed wheel when the segment 156 of the cam engages the follower roller 155 to permit a single revolution of the feed wheel at each operation of the machine.

The follower roller 155 is yieldably held in engagement with the cam 105 by means of a spring 159 connected at its opposite ends with the follower 154 and a lug 160 formed on the frame 55, as seen in Fig. 4.

Intermediate the shafts 135 and 136 I provide a transversely disposed rock shaft 161 which is journaled in the bracket 139 and also in an elongated bearing 162 on the main housing. Said rock shaft has fixed to the outer portion thereof intermediate the pulleys 142 and 143 an actuator finger 163 which has a curved upper extremity 35 164 normally disposed above the path of the mail matter and consequently above the periphery of the feed wheel 147.

It may be understood at this point that the purpose of the actuator 163 is for insuring the extension of the operative printing die 63 outwardly to the printing circle in advance of the arrival of a piece of mail matter at the point of contact between the printing cylinder 44 and the impression roller 118. The cam 105 serves to extend the printing dies or rather one of the printing dies at each revolution of the printing member 44 just prior to the time the forward edge of the die reaches a point of engagement with a yieldable inking roller 165 which is shown in Fig. 11.

Inasmuch as the actuator finger is operated by the engagement of the forward edges of the pieces of mail matter, if and when no piece of matter is being advanced to printing position, the printing dies will be retracted by reason of the contour of the cam face 105 prior to contact between the inking roller 165 and the printing die. If and when, however, a piece of matter depresses the finger 163 at the proper time the mechanism I am now about to describe in connection with said finger will retain the printing die in extended position until it has been inked by the roller 165 and further until it has passed the printing position.

To this end the bracket 108 which supports the yoke 106 is provided at its bottom with a latch 166 which is pivoted on a vertical axis and held in position by means of a screw 167. Said latch has an outer curved face 168 which, when the yoke has been actuated by cam 105, is adapted to move under a depending lug 169 on the yoke and hold the yoke and cam 44' in extended position, the follower roller 110 being, in such case, held out of engagement with the cam 105.

The latch 166 is pivotally connected at 170 75 with a longitudinally extended bar 171 and said

bar has an elongated slot 172 in its outer end which is engaged by a depending notched portion 173 of a bracket 174, as shown in Figs. 5, 6 and 8. Said bracket has an upwardly turned end 175 which is adjustably held on the face of a yoke bracket 108 and serves to support the bar 171 in such a manner that the right hand end thereof, as seen in Fig. 5, may be slightly elevated and yet supported on the portion 173 of the bracket.

The actuator rock shaft 161 carries a pair of collars 176 and 177 which are spaced apart on and are fixed to the shaft. The collar 177 has a lug 178 thereon which engages a lug 179 on the bearing 162 for limiting the movement of the collar in a clockwise direction, as seen in Fig. 5. The collar 176 has an arm 180 which is tensioned on the bracket 174 by means of a spring 181. Intermediate the collars 176 and 177 I provide an arm 182 which is loosely mounted on the shaft 161 and the upper end of said arm is adapted to engage the end of the bar 171. The collar 176 has a lug 183 thereon which engages the arm 182 for normally urging said arm in a clockwise direction to a normal position, as shown in Fig. 5. The arm 182 is differentially yieldable on the shaft 161 relative to the collar 176 by means of a coil spring 184 which has one end engaged with the lug 178 on collar 177 and its other end overlying the edge of arm 182.

The rock shaft 153 carries an arm 185 which is connected with the bar 171 by means of a tension spring 186, said spring connection being such that it will tend to urge the bar 171 to the right and also downwardly, as seen in Fig. 5.

The mechanism is so timed that just following the extension of the printing die 63 by the cam 105, the advance of a piece of mail matter into the machine will depress the actuating finger 163 and thus rock shaft 161 in a counter-clockwise direction, as seen in Fig. 5, thereby rocking arm 182, and forcing the bar 171 to the left. The movement to the left of the bar 171 moves the latch 166 under the lug 169 of the yoke 106, thus serving to hold the cam 44' and the printing members 63 in extended position. A very slight movement of arm 182 and bar 171 will permit the arm to slide under the end of bar 171 and the tension of spring 186 then tends to restore the bar 171 to its normal position. Such movement of the bar is prevented, however, by reason of the friction of the yoke 106 on the latch 166, and the printing die will be held in extended position until the completion of the printing operation.

If perchance the printing operation is not completed when the rear end of a piece of mail matter has advanced beyond the finger 163, the restoration of the finger by reason of the tension of the spring 181 will also restore the arm 182 to normal position, even tho the bar 171 is held up for a further period.

In order to insure the locking of the bar 171 against retraction when a letter is advanced to printing position and if the friction of the yoke 106 on the latch 166 is insufficient, or should the pressure thereon be relieved, I provide the arm 185 with a spring held pawl 187 which, when the bar 171 is moved forwardly, will engage the left hand end of the slot 172 in the bar and prevent the restoration of said bar. This pawl is so arranged that when the arm 182 is restored prior to the restoration of the bar 171, said bar may be elevated and disengaged from the pawl 187, for under such conditions the printing operation would be in progress and the bar could not possibly be retracted until such operation was completed.

The machine is provided, as shown in Fig. 1, with a feed hopper 188 which is suitably attached to the left hand side of the machine and provides a bed for the receipt of the mail matter. The feed hopper 188 is provided with a yieldable frictional separating member 189 which is mounted on an end 190 of the hopper. Said member is disposed between the flanges 149, 149 of the feed wheel 147 and is adjustable relative thereto so that it will exert friction on all but the lowermost letter in a stack for preventing the advance of such letters into the grip of the machine.

Above the belts 144 and 145 I provide a pair of idler rollers 191, 191 which are mounted on a bracket 192 pivotally supported at 193 on the web 6 of the machine and yieldable relative to said belts. Said rollers are yieldably held in engagement with the belts 144 and 145 by means of a spring 193' which is carried on the screw 193 and is tensioned so as to urge the bracket 192 and the associated rollers downwardly.

As described in my said pending application, I provide flanges 149 of the feed wheel with peripheral recesses 194 which are transversely aligned and serve to form seats for the forward edges of the letters or cards so that the lowermost letter of a stack will always seat in said notches preparatory to advancement to printing position when the wheel 147 is released for clockwise rotation, as seen in Fig. 11.

Now reverting to the connection between the register units 21 and 22 and the printing member 44, reference is made to Figs. 13, 14, 16 and 17 and also to Fig. 2. The member 59 of the printing cylinder is provided with a rearwardly extended hub 195 which telescopes the hub 86 of cam 44'. The hub 195 is provided with a plurality of helical threads 196 on its outer periphery which engage a collar 197. Said collar is non-rotatable by reason of a plurality of pins 198 which are fixed to the gear member 91 and are adjustable in bores of the collar. The threads 196 have a long lead so that the printing cylinder 44 may be adjusted to four different positions on the shaft 43 with the movement of the collar 197 to the full length of the hub 195. The register operating shaft 29 carries a gear 198 thereon which constantly meshes with a pinion 199 on a counter-shaft 200. The gears 198 and 199 have elongated hubs 201 and 202 respectively which are provided with annular grooves on their forward ends and the collar 197 is also similarly provided with an annular groove, which grooves are adapted to be engaged by a yoke 203 as shown in Fig. 14 so that the longitudinal movement of the collar 197 and gears 198 and 199 will be moved to a corresponding extent when the printing cylinder is adjusted for printing stamps of different denominations.

The yoke 203 carries a detent 204 which is pivoted thereon at 205 and is tensioned by means of a spring 206 so that the free end 207 thereof will engage the notches in a star wheel 208 on the hub 201 of gear 198 for preventing the rotation of gears 198 and 199 to more than a predetermined extent of movement. The composite gear 91 is adapted to selectively mesh with the pinion 199 during a portion of a revolution of the gear 91. The width of the pinion 199 is slightly less than the space between the several series of gear teeth on the composite gear.

As shown, for instance, in Fig. 2, the mechanism is set to print a stamp of the lowest possible denomination with the type of mechanism illustrated, viz: a 1¢ stamp. The gear 198, for in-

stance, has twenty teeth, and gear 91 is of the same nominal pitch diameter as gear 198. Thus the series 92 of gear teeth on the gear 91 comprising but two teeth will, when the cam 44' is extended by the yoke 106, align the teeth 92 with the pinion 199, and when the printing die 63 for the 1¢ denomination has been extended by the movement of cam 44' the teeth 92 will engage and rotate the pinion 199 and the gear 198 for a distance equal to twice the circular pitch of the 10 gears. This will be to the extent of one-tenth of a revolution and would register 1¢ on the two register units 21 and 22 each time the gears are so operated.

When a 2¢ stamp is to be printed, the setting 15 knob 74 is pulled outwardly against the tension of spring 76 so as to disengage it from the cap 70, and the printing cylinder 44 is then rotated on its shaft 43 until the knob 74 registers with the 2¢ aperture of slot 73 on the member 74. This movement of the printing cylinder 44 will effect the longitudinal movement of collar 197 and gears 198 and 199 rearwardly until the pinion 199 occupies a plane between the series of teeth 92 and 93 on gear 91. Thereafter at each time a printing 20 operation is effected the teeth 93 will engage the pinion, and there being four teeth in this series the gear 98 will be rotated for one-fifth of a revolution and will register 2¢ on the registers. Likewise as the collar 197 is adjusted further 30 rearwardly a 3¢ or a 4¢ stamp may be printed by operatively positioning the pinion 199 between the teeth 93 and 94 and between the teeth 94 and 95 respectively.

The rotation of the printing cylinder in a 35 clockwise direction, as seen in Fig. 1, for but a fraction of a revolution is prevented by means of a spring held detent 209 pivoted at 210 to the meter cover 5 and adapted to engage a ratchet 211 with a plurality of regularly spaced teeth 40 thereon formed on the gear 80.

Each of the printing dies 63 detachably supports a dater unit 212 thereon which may be detachably held in position by means of a spring 213 or otherwise. Said dater is adapted to print 45 the indicia shown at 214 in Fig. 18 including the name of the city and state, the month, day of the month, and the year.

In operation, when the printing cylinder has been set as hereinbefore described to print a 50 given denomination of stamps a stack of letters are deposited in the feed hopper 188 and power is applied to the machine. The letters will be fed successively in single file to printing position by means of the belts 144 and 145 and the associated rollers 191. The feed wheel 147 times the advance of the successive letters to printing position and the movement of the letters over the finger 163 renders the printing die 63 operative for imprinting the authorized indicia 69 60 on the letters.

The gear 91 is adjusted so that it will successively register each impression on the two counter units, but when and if a letter fails to immediately follow another to printing position 65 the printing die will be retracted before incoming position is reached and the registers will not be operated.

As hereinbefore stated, the meter is set by authorized officials of the Post Office for a pre-determined number of impressions and is then locked and sealed against unauthorized access. When the authorized impressions have been exhausted, as shown by the meter, the register units are locked against further operation and 75

the printing cylinder is also locked so that no more impressions may be printed until the meter has been reset.

What I claim is:

- 5 1. A postage meter comprising in combination with means for feeding mail matter to printing position, a rotatable printing member having a plurality of printing dies of different denominations arranged at different points about 10 the axis of said printing member, means for selectively rendering certain of said printing dies in a printing operation while the other dies are inoperative, at will, means preventing the 15 operation of said operative die during the rotation of said printing member except when pieces of matter are advanced to printing position, and an impression member cooperating with said printing member whereby to imprint upon and move mail matter from printing position.
- 20 2. In a postage meter the combination with a rotatable printing member, an impression member associated therewith, and means for feeding mail matter into position between said printing member and said impression member, of a 25 plurality of printing dies circumferentially spaced apart on the printing member, manually operable means for selectively rendering one of said printing dies capable of successive printing operations while the other dies are incapable of printing 30 operations during the rotation of said printing member, said operative die being manually retracted from printing position and extensible to printing position only when mail matter is advanced to the printing means.
- 35 3. A postage meter comprising in combination with a rotatable printing member and an impression member associated therewith, of means for feeding successive pieces of mail matter into positions between said printing member and said impression member, a plurality of printing 40 dies extensively mounted on said printing member, means for rendering one of said printing dies operative at will for successive printing operations while the remaining dies are locked 45 against operation, said operative die being normally retracted from printing position, and means automatically effective during the rotation of said printing cylinder for extending the 50 operative printing die to printing position for engagement with the mail matter.
- 55 4. A postage meter having a rotatable printing head, a plurality of printing dies thereon of different denominations, said dies arranged circumferentially on the printing head, means for rendering one of said dies operative while the remaining dies are held inoperative, means automatically operable at each revolution of said head for rendering the operative printing die effective for printing when a piece of mail matter 60 is moved by the printing means and ineffective when no piece of mail matter is so moved, and a rotatable impression member adjacent said printing member as and for the purpose described.
- 65 5. A postage meter having a rotary printing head, a plurality of printing dies of different denominations circumferentially spaced apart on said head, means for advancing successive pieces of mail matter to and from printing position at regular intervals including a rotary impression 70 member, means for selectively rendering one of said printing dies operative and the remaining dies inoperative at will, and means controlled by the advance of the mail matter to printing position for rendering the operative printing die effective for printing postage indicia thereon.
- 75 6. A postage meter comprising a rotatable printing head, a plurality of printing dies of different denominations circumferentially arranged on said head, means for extensively supporting said printing dies, means for selectively rendering one of said dies operative for printing operations and for locking the remaining dies retracted from printing position, means for advancing successive pieces of mail matter to and from printing position, and means controlled by the advance of the mail matter to printing position for extending the operative die to printing position at a given point in each revolution of said head. 5
- 80 7. A postage meter comprising a rotatable printing head, a plurality of printing dies of different denominations circumferentially arranged and radially slidable thereon to and from operative positions, means for selectively unlocking and extending one of said dies to operative position 20 and for locking the remaining dies in inoperative position, means for advancing successive pieces of mail matter to and from printing position, and means controlled by the advance of the mail matter to printing position for rendering the 25 operative printing die effective for printing postal indicia on the mail matter.
- 85 8. A postage meter comprising a rotatable printing head, a plurality of printing dies of different denominations circumferentially arranged and radially slidable thereon, means for permitting the extension of one of said dies to printing position and for holding the remaining dies retracted during the rotation of said head, said operative die being normally retracted from 30 printing position, and means for automatically extending the operative printing die at the same point in each revolution of the printing head for successive printing operations.
- 90 9. A postage meter comprising a rotary printing head, a plurality of printing dies of different denominations successively arranged and concentrically positioned thereon, means for holding certain of said dies retracted inwardly of the periphery of said head and for permitting the extension of other of said dies outwardly of the periphery thereof, said operative die being normally retracted from printing position, and means automatically operable at a given point in each revolution of said head for extending 40 the operative printing die to printing position for the purpose of printing authorized postal indicia on matter advanced by the printing head. 45
- 95 10. A postage meter comprising in combination, means for feeding mail matter to printing 55 position, a rotatable printing member having its periphery disposed adjacent the path of the mail matter, a spindle for rotatably supporting said printing member, a plurality of printing dies of different denominations extensibly mounted 60 on said printing member and adjustable to and from different points on the periphery of the printing member, means for selectively connecting the printing member with the spindle for rendering one of said printing dies operative 65 at the same point in the revolution of the spindle, and means controlled by the movement of the mail matter to printing position for extending the operative die to printing position on the printing member, and simultaneously locking the 70 inoperative dies in retracted position.
- 100 11. A postage meter as characterized in claim 10, including a manually operable member associated with said printing member and said spindle for adjusting the printing member rela- 75

tive to the spindle when one die is operative and other dies are inoperative.

12. A postage meter as characterized in claim 10, including a manually operable member associated with said printing member and said spindle for adjusting the printing member relative to the spindle when one die is operative and other dies are inoperative, and means for visibly indicating the operative die.

13. A postage meter comprising in combination with means for feeding mail matter to printing position, a rotatable printing member having a plurality of printing dies of different denominations arranged at different points about the axis of said printing member, a sleeve coaxially mounted with respect to the printing member and operatively engaging said dies, a cam on said sleeve engaging said dies, means controlled by the movement of mail matter to printing position for reciprocating said sleeve and said cam for simultaneously extending one of said dies to printing position and locking the inoperative dies against extension, and means for manually and selectively rendering said dies operative and inoperative at will.

14. A postage meter comprising in combination with means for feeding mail matter to printing position, a rotatable printing member having a plurality of printing dies of different denominations arranged at different points about the axis of said printing member, a sleeve coaxially mounted with respect to the printing member and operatively engaging said dies, a cam on said sleeve engaging said dies, means controlled by the movement of mail matter to printing position for reciprocating said sleeve and said cam for simultaneously extending one of said dies to printing position and locking the inoperative dies against extension, a spindle for rotatably supporting said printing member and coaxially mounted relative to said sleeve and said printing member, and means for adjusting the printing member on said spindle to render certain of said dies operative and certain other dies inoperative at will.

15. A postage meter comprising in combination with means for feeding mail matter to printing position, a rotatable printing member having a plurality of printing dies of different denominations arranged at different points about the axis of said printing member, a sleeve coaxially mounted with respect to the printing member and operatively engaging said dies, a cam on said sleeve engaging said dies, means controlled by the movement of mail matter to printing position for reciprocating said sleeve and said cam and for extending one of said dies to printing position, said cam being effective for locking the inoperative dies against extension, a spindle for ro-

tatably supporting said printing member and coaxially mounted relative to said sleeve and said printing member, means for adjusting the printing member on said spindle to render certain of said die operative and certain other dies inoperative at will, and means for visibly indicating the operative die.

16. A postage meter comprising in combination with means for feeding successive pieces of mail matter to printing position, a power operated mechanism, a spindle connected with said power operated mechanism, a rotatable printing member supported on and adjustable to different positions on said spindle, a housing enclosing said printing member against unauthorized access, a plurality of printing dies of different denominations extensibly mounted on said printing member, means controlled by the movement of mail matter to printing position for extending said dies to operative position on the printing member, and means externally of said housing and connected with said spindle and with said printing member for adjusting the printing member on the spindle for rendering a given die operative and for simultaneously rendering the remaining dies inoperative at will.

17. A postage meter comprising in combination with means for feeding mail matter to printing position including an impression member, a rotatable printing member having a plurality of printing dies of different denominations arranged at different points about the axis of said printing member, means for enclosing said printing member and said dies against unauthorized access, means for selectively rendering one of said printing dies operative and other of the dies inoperative at will, and means preventing the operation of said operative die during the rotation of said printing member except when pieces of matter are advanced to printing position.

18. A postage meter comprising in combination with means for feeding mail matter to printing position including an impression member, a rotatable printing member having a plurality of printing dies of different denominations arranged at different points about the axis of said printing member, means for enclosing said printing member and said dies against unauthorized access, means for selectively rendering one of said printing dies operative and other of the dies inoperative at will, means preventing the operation of said operative die during the rotation of said printing member except when pieces of matter are advanced to printing position, and means accessible to an operator for adjusting said printing member to render a selected die operative and the remaining dies inoperative at will.

LUTHER L. MACK.
